(57) **CLAIM**

I claim the ornamental design for a pet water fountain, as shown and described.

DESCRIPTION

FIG. 1 is a top, front, right perspective view of a first embodiment of a pet water fountain of my new design; FIG. 2 is a bottom, back, left side perspective view thereof; FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an exploded top, front, left side perspective view of a first embodiment, shown disassembled for completeness of illustration.

FIG. 10 is a top, front, right perspective view of a second embodiment of a pet water fountain;

FIG. 11 is a bottom, back, left side perspective view thereof;

FIG. 12 is a front view thereof;

FIG. 13 is a back view thereof;

FIG. 14 is a left view thereof;

FIG. 15 is a right view thereof;

FIG. 16 is a top view thereof;

FIG. 17 is a bottom view thereof; and,

FIG. 18 is an exploded top, front, left side perspective view of a second embodiment, shown disassembled for completeness of illustration.

The broken lines in the drawings depict portions of the pet water fountain that form no part of the claimed design.
